UNITED STATES PATENT OFFICE

GEORGE H. SCHRODER, OF OAKLAND, CALIFORNIA

CLAMPING TONGS FOR SHOE REPAIRING

Application filed June 18, 1928. Serial No. 286,098.

This invention resides in the provision of a new and useful device for use in mending shoes, which device is in the nature of a clamp for holding in proper position, invisible patches used to mend cracks and other breaks in the uppers of shoes. The device of this invention does away with the old method of stitching a crack or tear in the shoe across the outer side of the upper, also the old method which consists of lasting the shoe and applying elastic bands to bind the patch. Doing away with these former practices, a great deal of time may be saved and a better mending job provided for with the clamp of this invention.

One of the purposes of the invention is to provide a clamp of the character described which is simple as to construction, inexpensive and capable of being quickly and easily put into use to properly apply an invisible patch on the inside of an upper of a shoe.

With the above mentioned and other objects in view, the invention consists in the novel construction and combination of parts hereinafter described, illustrated in the accompanying drawings, and set forth in the claims hereto appended, it being understood that various changes in the form, proportion, size and minor details of construction within the scope of the claim may be resorted to without departing from the spirit or sacrificing any of the advantages of the invention.

35 Referring to the drawings:

Fig. 1 represents a top plan view of the clamp of this invention showing in dotted lines, the jaws as they appear when open.

Fig. 2 is a side elevation of the clamp. 40 Fig. 3 is a perspective view showing the manner of using the clamp to apply an inside patch to the upper of a shoe.

The embodiment of the invention shown in detail in the accompanying drawings 45 comprises two resilient metal strips 1 and 2, secured together by means of a U-shaped spring metal piece 3 attached to the members 1 and 2 by suitable fastenings 4. It is in this manner that the strips 1 and 2 are disposed in spaced parallel relation from

certain ends to points approximately centrally of their ends, from which latter points said members 1 and 2 are diverged, and define handle portions generally designated 5. On the outer ends of the parallel portions of the strips 1 and 2 are circular jaws 6 and 7 made of firm, resilient material such as rubber or the like, and having smooth opposed faces. These jaws are provided on their rear face with knob portions 55 8 around which the strips 1 and 2 are bent in the form of an eye as shown in dotted lines at 9 in Fig. 2. One of the spring pieces 3 is enlarged and formed with an eye 10 to provide for hanging the clamp 60 65 from a nail or like projection.

In the operation of the clamp, a skived patch of leather is inserted at the crack, rip or tear, in the upper of the shoe which is to be mended, so that the patch will lie between the lining and the leather of the upper, or, if no lining, will lie on the inside of the shoe just beneath the crack, rip or tear. Sole cement or the like, is then applied inside the crack or rip and around the 70 skived leather patch. The clamp is then opened and positioned so that one jaw will be disposed on the inside of the shoe, pressing over or on the patch, and the other jaw will lie on the outside of the shoe over the 75 rip or break to be repaired. The jaws will yieldingly but firmly apply pressure to the patch, and said clamp is allowed to remain in place until the cement has dried, this 80 usually being about thirty minutes. The 85 spring piece 3 causes the jaws to be firmly forced against the patch and shoe upper so that the patch will be applied by pressure and caused to properly adhere in place.

The use of my clamp in the manner herein 90 described provides for a quicker mending of shoes, and makes for a better appearing and more lasting "mend" job than heretofore.

I claim:

A clamp for use in mending shoes comprising arms; spring means joining said arms between the ends thereof and normally forcing certain free ends of the arms towards one another; rubber jaw members 100

having flat opposed faces carried on certain free ends of said arms, said jaw members having knobs on the outer sides thereof; and eyes formed on said arms and surrounding said knobs to hold the jaws in place.

GEORGE H. SCHRODER.
